UNITED STATES PATENT OFFICE

2,589,479

DOOR OPERATOR.

Guy A. Curtis, Cleveland Heights, Ohio, assignor
to United States Motors Corporation, Oshkosh,
Wis., a corporation of Wisconsin

Application August 31, 1948, Serial No. 46,956

1 Claim. (Cl. 268—59)

1 This invention relates to improvements in door operators, more particularly power driven operators for garage doors of the overhead sliding type. Heretofore operators for this type of door have embodied reversible motors which are more expensive than motors designed to turn always in the same direction and which require somewhat complicated electrical circuits for their control.

The present invention utilizes a motor which turns in one direction only and an endless chain the opposite runs of which are connected one at a time to the door for moving it in opposite directions. The opening of the motor circuit is effected automatically as the door arrives at fully open or fully closed position.

One of the objects of the invention is the simplification of door operating mechanism of the character stated.

Another object is the provision of a door operating mechanism embodying a carriage which moves back and forth in a given path when pushed by one or the other of the two runs of an endless chain driven always in the same direction.

Another object is the provision of control means for automatically breaking the motor circuit as the door completes its movement in either the opening or closing operation.

A further object is the provision of power driven door operating means which will not interfere with manual operation of the door.

Still another object is the provision of means in connection with power operation to automatically lock the door at the end of the door closing operation, or to unlock it at the beginning of the door opening operation, which locking means is susceptible also of manual operation.

Other objects and features of novelty will appear as I proceed with the description of that embodiment of the invention which, for the purposes of the present application, I have illustrated in the accompanying drawings, in which

Fig. 1 is a vertical sectional view of a garage door provided with my improved operating mechanism, and a diagram of the motor circuit and control circuits therefor, the parts being shown in the position which they occupy at an intermediate point of the door closing movement.

Fig. 2 is a fragmental view of the driven sprocket wheel and cooperating chain with the parts in the position which they occupy when the door is about to start its movement toward closed position.

2

Fig. 3 is a vertical sectional view taken substantially on the line 3—3 of Fig. 2.

Fig. 4 is a perspective view of the sliding carriage to which the door is connected.

5 Fig. 5 is a fragmental elevational view of the inner side of the door in closed position.

Fig. 6 is a cross-sectional view of the door and its connection to the power operator, together with locking means, and

10 Fig. 7 is a perspective fragmental view showing the lock disassembled.

Referring first to Fig. 1 of the drawings, there is shown a garage door formed of several elongated sections or panels 10 hinged together horizontally and provided at its side edges with laterally projecting shoes 11 running in tracks, each of which is composed of straight sections 12 and 13 and an interconnecting curved section 14.

In an overhead position beneath the ceiling or

20 roof 15 of the garage there is mounted a guide 16 extending rearwardly from the door opening of suitable cross-sectional shape, it being shown in the present instance as a tubular element of square cross-section with a longitudinal slot 17 along its bottom side. Near the two ends of the guide 16 shafts 18 and 19 are journaled in the side walls of the guide, and upon these shafts between the two side walls sprocket wheels 20 and 21 are fixed. An endless chain 22 runs over these sprocket wheels.

25 Carriage 23 is mounted to slide back and forth within the guide 16. As is illustrated herein the carriage 23 comprises two members 24 and 25 that are joined together by a metal strap 26 in which are formed a series of perforations 27 that are adapted to take the shanks of bolts 28. These bolts extend through spacing washers 29 and are screwed into threaded openings in the base portions of members 24 and 25. A bracket 30 extends downwardly from strap 26, and to it there is pivoted a link 31 which is connected with the uppermost section 10 of the door. By selecting the holes 27, members 24 and 25 may be spaced different distances from bracket 30 for adjustment purposes.

30 As the carriage 23 moves back and forth in guide 16 the door slides up and down along its track 12, 13, 14, its two extreme positions being indicated by broken lines in Fig. 1. Carriage 23 is mounted to slide back and forth within the guide 16. As is illustrated herein the carriage 23 comprises two members 24 and 25 that are joined together by a metal strap 26 in which are formed a series of perforations 27 that are adapted to take the shanks of bolts 28. These bolts extend through spacing washers 29 and are screwed into threaded openings in the base portions of members 24 and 25. A bracket 30 extends downwardly from strap 26, and to it there is pivoted a link 31 which is connected with the uppermost section 10 of the door. By selecting the holes 27, members 24 and 25 may be spaced different distances from bracket 30 for adjustment purposes.

35 As the carriage 23 moves back and forth in guide 16 the door slides up and down along its track 12, 13, 14, its two extreme positions being indicated by broken lines in Fig. 1. Sprocket wheel 21 is an idler wheel, while sprocket wheel 20 is driven by a pulley 23 keyed to shaft 18 outside the guide 16. A belt 34 runs over pulley 23 and over a small pulley 9 fixed upon the shaft of a non-reversible back geared electric motor 35.

40 45 50 55 The carriage member 24 is provided with a

pair of projections 36 spaced apart sufficiently to permit the lower run of chain 22 to pass between them. At the upper side of carriage member 25 there are two similar projections 37 between which the upper run of the chain may pass. 38 is a pin welded or otherwise fixed to chain 22 and extending transversely thereof, the pin being longer than the space between the two projections 36 or 37, as shown in Fig. 3. At the opposite point of the chain, that is at the maximum possible distance along the chain from pin 38 there is another pin 39 which may be similar to pin 38, except that it must be short enough to pass between the two projections 36 or the similar projections 37. When pin 38 is traveling in the upper run of the chain it engages the projections 37 and causes the carriage to travel toward the right. When it is traveling in the lower run of the chain it engages the projections 36 and pushes the carriage toward the left. When the carriage reaches either of the extreme positions indicated by broken lines in Fig. 1, pin 38 moves in a semicircle around the sprocket wheel 20 or 21, as the case may be, thereby disengaging itself from the projections 36 or 37 and moving into the opposite run of the chain. The adjustments of the carriage with respect to the bracket 30 are such that at the times when the pin 38 leaves the projections on the carriage the door is either fully open or fully closed.

The casing of an electric switch of the micro-switch type is illustrated at 41. Projecting downward from this casing is a plunger 42 biased downwardly and toward switch closing position. An actuating arm 43 is hinged at 44 to casing 41. When either of the pins 38 and 39, in traveling upwardly around sprocket 20 engages arm 43, that arm swings counterclockwise through a small angle, lifting the plunger 42 and opening the switch. This action results in stopping the motor by means of electrical connections which will now be described.

A 110 volt supply line is indicated at 50 and 51. The primary coil of a step-down transformer 52 is connected into this circuit. The secondary coil of the transformer is connected into one side 53, 53' of a low voltage line which runs to an electromagnet 54, a return conductor 55 being connected to the other end of the magnet coil. Conductors 53 and 55 may be joined electrically by a suitable switch 56 which is biased toward open position. The switch 56 may be a manually operated push-button or any other type of switch which tends to open when not held closed. When electromagnet 54 is energized by the closing of switch 56, an armature 57 is drawn into engagement with a contact 58, thereby joining conductor 50 with a conductor 59 leading to the motor 35, from which another conductor 60 goes to the wire 51 of the supply line.

In order that the motor circuit when thus completed may be maintained closed through one cycle of door operation, I provide a holding circuit bridged across the terminals of the secondary coil of the transformer 52, which consists of conductor 53' going to the magnet coil, a short length of conductor 55, a conductor 62 leading to a contact 63, an armature 64 held in operative relation with contact 63 by the force of the magnet when energized, a conductor 65 leading to switch 41 and a return conductor 66 back to the opposite side of the secondary coil of the transformer.

When the door is closed the link 31 stands at an angle of about 45°. Therefore, when the door

is lifted by hand from closed position the link 31 imparts motion to the carriage which moves it toward the left in its guide 16. In this manual opening of the door the carriage slides in the guide 16 away from the pin 38 to its extreme left-hand position as illustrated in Fig. 2. Closing the door manually will bring the carriage back to the Fig. 6 position, the chain of course remaining stationary during both manual operations.

I provide locking means which functions automatically on power operation of the door and manually on manual operation. In the illustrated embodiment this locking means comprises a metal guide 70 secured to the top of the door, in which a bolt 71 is mounted to slide. This bolt is biased toward locking position by a tension spring 72 that is attached at its ends to posts 73 and 74 projecting upwardly from the guide and bolt respectively. This spring tends to hold the forward end of the bolt in engagement with a metal keeper 75 in the door frame, and also to cause the bolt to snap into the keeper when the door is closed.

At the rear end of the bolt there is a slot 76 which receives a pin 77 carried at one end of link 31, by which the bolt is pulled out of its keeper when the carriage starts its travel toward the left. Hence the door is locked automatically when it moves into closed position and is unlocked automatically when the power operator starts on the door opening movement.

In order that the door may be unlocked manually in the event that the electric operator fails to function for lack of current or otherwise, I provide a manual actuator for bolt 60 which may take the form herein illustrated. In this embodiment a bell crank lever 78 is pivoted to the door at 79. In the upright arm of this lever there is a slot 80 which receives pin 77. From the horizontal arm of the lever a cable 81 extends downwardly along the inner wall of the door through a ring guide 82. Its lower end is eccentrically attached to a round bar 83 which projects through the door and is provided on the forward side thereof with handles 84 by means of which it may be turned to exert a pull on cable 81 and thereby to tilt bell crank 78 and withdraw the bolt from engagement with its keeper 75. Bar 83 may be locked against rotation by any suitable means adapted for actuation by a key 85.

Operation. Assuming that the carriage 23 is in the broken line position at the left end of the guide 16, which is the same as the full line position of Fig. 2, the door being then fully open and the pin 38 occupying the dotted line position of Fig. 2 in which the switch 41 is open, and assuming that the operator wishes to set the mechanism into operation for closing the door, he may close switch 56 momentarily by manual actuation or through the intermediacy of an electrical impulse set in motion by any desired means. This will energize magnet 54, causing armatures 57 and 64 to engage contacts 58 and 63 respectively. The motor circuit is thereby completed and the motor starts to turn the sprocket wheel 20 clockwise. Pin 38 immediately moves upwardly out of engagement with actuating arm 43, which permits that arm to swing downwardly through an angle sufficient to permit plunger 42 to descend and cause closing of switch 41. As soon as this occurs the holding circuit 53', 54, 55, 62, 63, 64, 65 and 66, is completed through switch 41 and the switch 56 may

be permitted to open without affecting the motor circuit. As the chain travels due to rotation of sprocket wheel 20, pin 38 moves from the dotted line position of Fig. 2 to the full line position of that figure, when it engages the projections 37 and pushes carriage 23 toward the right, and the carriage working through strap 26, bracket 30 and link 31 pushes the door to the right and downward, as viewed in Fig. 1. This continues until the carriage reaches the position of Fig. 6, when the bolt 71 snaps into the keeper 75. Then pin 38, by turning around sprocket 21, moves downwardly in an arc out of engagement with projections 37. At the same time that pin 38 reaches the level of shaft 19, pin 39 moves upwardly around sprocket wheel 20 into engagement with switch actuating arm 43, thereby opening the control circuit, deenergizing the magnet 54 and breaking the motor circuit at the point 57, 58. Thus the chain movement comes to a stop. In installing the door some adjustment of the strap 26 relative to the carriage 23 may be necessary in order to insure full closing of the door when the motor stops. When the operator wishes to open the door the same procedure is followed, that is switch 56 is closed momentarily or until pin 39 clears actuating arm 43, closing the holding circuit. Shortly thereafter the pin 38 will strike the projections 36 and the carriage 23 will move toward the left, causing the link 31 to first pull out latch bolt 71 and then raise the door. The chain movement and the consequent carriage movement continue until the pin 38 engages actuating arm 43 and again brings about the opening of the motor circuit.

In case anything should happen which would prevent power operation of the door mechanism when the door is closed and locked, it may be readily opened by hand. To accomplish this it is necessary merely to insert and turn key 85, after which the bar 83 may be turned to exert a downward pull on cable 81, thereby turning bell crank lever 78 to withdraw bolt 71. The operator may then push the door upward and in-

ward along the track 12, 14, 13. This causes carriage 23 to travel to the left without affecting the chain 22 or the pins 38 and 39. The reverse operations will close the door and lock it.

Having thus described my invention, I claim:

Door operating mechanism comprising a straight hollow guide, a pair of sprocket wheels disposed within said guide near the ends thereof, an electric motor for turning one of said sprocket wheels in a given direction only, an endless chain running over said sprocket wheels within said guide, a two-sectional carriage slidable in said guide, a projection on one section of said carriage adjacent one run of said chain, a projection on the other section of said carriage adjacent the other run of said chain, said projections being spaced apart a substantial distance longitudinally of said guide, means adjustably connecting said sections of the carriage for varying the spacing relationship of said projections, a link connected to said carriage and adapted to be attached to a sliding door, and a transverse pin on said chain adapted to engage one of said carriage projections for pushing the carriage in one direction when travelling in one run of the chain and to engage the other of said projections for pushing the carriage in the opposite direction when travelling in the other run of the chain.
